CLAIM

The ornamental design for a lip tape, as shown and described.

DESCRIPTION

FIG. 1 is a perspective view of the design of this invention; FIG. 2 is a top view;

FIG. 3 is a bottom view;

FIG. 4 is a side view;

FIG. 5 is a second side view;

FIG. 6 is a third and fourth view; and,

FIG. 7 is another perspective view thereof.

The broken lines in the drawing are for illustrative purposes only and form no part of the claimed design.
